ATTORNEY

UNITED STATES PATENT OFFICE.

MARIE HACKER, OF ALLENHURST, NEW JERSEY.

BUST-SUPPORTER.

1,262,332.

Specification of Letters Patent.

Patented Apr. 9, 1918.

Application filed September 12, 1917. Serial No. 191,028.

To all whom it may concern:

Be it known that I, MARIE HACKER, a citizen of the United States, residing at Allenhurst, in the county of Monmouth and State 5 of New Jersey, have invented certain new and useful Improvements in Bust-Supporters, of which the following is a specification.

This invention relates to bust supporters and the object thereof is to provide a simply 10 constructed, cheap and efficient device of this character which may be worn either with or without a corset and which is especially useful in gymnasium work.

Another object is to produce a device of 15 this character which while effectively supporting the bust and holding it firmly against movement is yet cool and comfortable to wear.

With the foregoing and other objects in 20 view, which will appear as the description proceeds, the invention resides in the combination and arrangement of parts and in the details of construction hereinafter described and claimed, it being understood 25 that changes in the precise embodiment of the invention herein disclosed may be made within the scope of what is claimed without departing from the spirit of the invention.

30 In the accompanying drawings:—

Figure 1 represents a perspective view of 35 this improved supporter shown applied taken from the front of the wearer,

Fig. 2 is a similar view taken from the 40 rear, and

Fig. 3 is an enlarged detail front elevation of the meeting or connected ends of 45 the supporter shown arranged in juxtaposition ready for assembling, said view being 50 taken from the inside of the device.

The bust supporter constituting this invention is shown in the form of a body encircling member 1 adapted to pass around the wearer below the shoulder blades and 55 under the bust. Leading from the center of the back of said band or member 1 and secured thereto, being preferably made integral with said band, as shown at 2 are a pair of diverging shoulder straps 3 here 60 shown made integral with the body encircling member 1 although they need not necessarily be so made. These straps 3 which pass over the shoulders of the wearer in opposite directions have their free ends 65 connected, being here shown overlapped and provided at their connected terminals

with a fastening element in the form of a hook 4 which is designed to engage a co-operating fastening element in the form of an eye 5 shown attached to the body member at the center front thereof. Another fastening hook 4' is shown spaced inwardly from hook 4 to provide for the adjustment of the support to cause it to fit tightly or loosely at the will of the user. 60 65

The connected free ends of the shoulder straps 3 may be ornamented in any suitable manner, a rosette 6 being here shown for this purpose.

This supporter is preferably constructed 70 of a strip of elastic material folded midway its ends and crossed intermediately of said ends and secured as shown at 2 to provide the body encircling member 1 and the shoulder straps 3. This strip may be of any suitable or desired width being preferably about 75 one-half inch.

In the use of this improved supporter, the application thereof is accomplished by slipping the body encircling member 1 over 80 the head and arms with the shoulder straps hanging down the back. The member 1 is then adjusted as high under the bust as possible, with the fastening element 5 disposed at the center front thereof as is shown 85 clearly in Fig. 1. The suspenders or shoulder straps which are connected at their free ends are then brought up over the head of the wearer and one of the hooks 4 or 4' is engaged with the eye 5, and when so connected, the device will be in the position shown in Figs. 1 and 2, it being obvious that owing to its elasticity it will operate effectively to support the bust of the wearer and hold it firmly against movement, thereby 90 95 presenting a slightly appearance of a person not wearing a corset, or it may be used with a corset having a very low bust.

The shoulder straps 3 while they are here 100 shown made integral with the body encircling member 1 need not necessarily be so made and may be composed of any material found desirable. The elasticity of this device permits the wearer to freely move her body without in any way being discomfited by the support. 105

From the foregoing description, taken in connection with the accompanying drawings the advantages of the construction and of the method of operation will be readily apparent to those skilled in the art to which 110 the invention appertains and while I have

described the principle of operation of the invention together with the device which I now consider to be the best embodiment thereof, I desire to have it understood that the device shown is merely illustrative and that such changes may be made as are within the scope of the claimed invention.

I claim:-

1. A bust support comprising a body encircling member with shoulder straps secured to said member at the center of the back thereof and having their other ends engaged with each other and secured to the center front of said body encircling member.
2. A bust support comprising a body encircling band with shoulder straps extending from the center of the back of said band and having their free ends connected, said straps forming one member of said support and the band another, one of said members being elastic, the free ends of said straps being connected to the center front of said band.
3. A one-piece bust support comprising a

body encircling member provided with 25 shoulder straps extending from the center of the back thereof and having their free ends united and coöperating fastening elements carried respectively by said united strap ends and by the center front of said body member whereby the device may be readily applied and removed.

4. A bust supporter comprising a strip of elastic material crossed at a point intermediate of its ends and secured at said point of intersection to form a body encircling member with diverging shoulder straps extended therefrom, the terminals of said straps being secured together, and coöperating fastening elements carried by said connected strap ends and by the center front of said body member, respectively.

In testimony whereof I affix my signature in presence of two witnesses.

MARIE HACKER.
